FELIX KÄPPLER, OF DRESDEN, GERMANY

DEVICE FOR MANUFACTURING CARDBOARD STRIP MATCHES IN BOOK-FORM

Application filed April 2, 1931, Serial No. 527,301, and in Germany April 8, 1930.

This invention relates to match making machines of the type wherein matches are made from a strip of paper-like material such as pasteboard.

5 More particularly, the invention relates to a device for paraffining and tipping the match splints after the strip has been slit to form such splints.

In machines of this class, a pasteboard-like strip is fed through the machine and is slit transverse its length, the slits extending inwardly from opposite edges of the strip and terminating in spaced relation to the longitudinal center line of the strip. Thus a series of match splints are formed at each edge of the strip.

The principal objects of the present invention are to provide a novel and efficient means for paraffining and tipping the free end portions of said splints; to provide a novel means whereby the strip is doubled longitudinally so that the splints at the opposite edges are in such position that both edge portions may be simultaneously dipped in a paraffin bath or positioned for tipping; and to regulate by novel means the extent to which said portions are dipped in said paraffin bath.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which—

Figure 1 illustrates a side elevation of a match making apparatus constructed according to this invention;

Figure 2 illustrates a side elevation, partly in section, of the paraffin bath and its associated parts;

Figure 3 illustrates a plan view of the apparatus disclosed in Figure 2;

Figure 4 illustrates a section on the line 4—4 of Figure 2;

Figure 5 illustrates a section on the line 5—5 of Figure 2; and

Figure 6 illustrates an enlarged section on the line 6—6 of Figure 1.

In the embodiment here shown, there is disclosed an apparatus having several sections whereof A indicates the supply section containing the roll 10 of pasteboard from which the strip 11 is fed through a cutting machine 12 located in the section B. From the section B the strip passes to the section C wherein is located the paraffining apparatus and from there to the section D containing the tipping apparatus. Finally, from the section D the strip passes to the drying section E. No attempt is here made to describe in detail the apparatus shown in sections A, B and E as the same is not claimed as the present invention. It may, however, be stated that the machine 12 slits the strip 11 from both edges toward the center, as indicated at 13 in Figure 3.

Considering now the paraffining apparatus, it will be seen that there is provided (see Figures 2 to 5) a stand or table 14. At the end of this stand near the machine 12 there is provided a pair of bearing standards 15 wherein are journalled a lower platen roll 16 and an upper creasing roll 17 so positioned that the strip as it passes between these rolls will be creased on its longitudinal center line. A guide 18 guides the strip 11 to proper position for entry between these rolls. Beneath the table at this end are bearings 19 wherein is journalled a shaft 20 driven by any suitable means such as the bevel gears 21 by which it is operatively connected to a drive shaft 22. Belt pulleys 23 on the shaft 20 and on a journal of the roll 16 are connected by a belt 24 so that the platen roll is rotated to feed the strip 11 in the direction of the arrows in Figures 2 and 3. On the table or stand 14 is a tank or vat 25 and secured to the sides of this tank are yokes 26 which straddle the tank. Carried by these yokes is a bar 27 having upturned ends 27' and fixed to the under side of this bar is a pair of strip bending members 28 tapered off at their ends. These members form an inverted V-shaped groove below the bar 27. Suitable means (not shown) are used to permit vertical adjustment of the bar 27. Supported in the tank 100

25 by suitable means (not shown) is a plate or bending strip 29 which is arranged vertically in the bath in alinement with the V-shaped groove. The upper corners of this 5 plate are rounded off, as shown in Figure 2. At the end of the table remote from the rolls 16 and 17 is a second pair of bearings 30 wherein are journalled the feed rolls 31, one of which carries a belt pulley 32 driven by 10 a belt 33 from a pulley 34 journalled in bearings 35. A belt 36 connects the pulley 34 and the pulley 23 on the shaft 20.

The tipping apparatus is somewhat similar, being provided with a stand 37 whereon 15 is a tank 38 carrying yokes 39 which support a bar 40. Beneath this bar is a pair of bending members 41 of rectangular form and spaced to provide a rectangular groove between them. Shafts 42 are journalled in the 20 sides of the tank 38 and carry concave rolls 43. These shafts are driven from the shaft 22 by bevel gears 44 and a sprocket and chain mechanism 45.

A paraffin bath 46 is held in the tank 25 25 and a tipping bath 47 is held in the tank 38.

As the strip is fed forwardly by the roll 16 it is creased down the center and upon reaching the bending members 28 and bending plate 29 starts to bend downwardly at 30 its edges, as shown in Figure 4, and the bending is continued as shown at Figure 5 so that the ends of the splints dip into the bath 46. The feed rollers 31 carry the strip, which is again flattened, to the tipping bath where 35 the bending operation is repeated but, in this case, the bending bar and strips are so spaced from the bath that the ends of the splints merely roll over the rolls 43 which pick up the tipping or heading composition and apply it to the splints. 40

It will be noted that the splints are radial or at right angles to the tangents of the profile of the concavity of the rollers.

I claim:

45 1. A device for paraffining strip matches comprising, in combination with a paraffining bath and guide rollers for moving the match strip over the bath, of a circular knife for scoring the strip longitudinally between 50 the match splint rows, a supporting plate placed edgewise in said bath, and a guide element arranged over said plate and operative to bend the strip over the plate edge for dipping the match splint ends into the bath.

55 2. In a device of the kind described, a tank, a bar extending longitudinally over the tank, of means forming a bending groove on the under side of the bar, a plate vertically alined below the groove and having its 60 upper edge entering said groove, and means for feeding a bendable strip between the upper edge of the plate and the walls of the groove.

65 3. In a device of the kind described, a tank, a bar extending longitudinally over

the tank, of means forming a bending groove on the under side of the bar, a plate vertically alined below the groove and having its upper edge entering said groove, and means for feeding a bendable strip between the upper edge of the plate and the walls of the groove, said last means including a creasing roller alined with the groove and adapted to crease the bendable strip. 70

4. In a device of the kind described, a tank, a bar extending longitudinally over the tank, of means forming a bending groove on the under side of the bar, a plate vertically alined below the groove and having its upper edge entering said groove, means for feeding a bendable strip between the upper edge of the plate and the walls of the groove, and feed rollers receiving and flattening the strip after passing the bending means. 75

In testimony whereof I affix my signature. 80
